EMIL C. WEISSINGER, OF MILWAUKEE, WISCONSIN, ASSIGNOR TO BUILDERS' NEEDS, INCORPORATED, OF MILWAUKEE, WISCONSIN, A CORPORATION OF WISCONSIN.

ORNAMENTAL MANTEL.

Application filed November 27, 1925. Serial No. 71,769.

The invention relates to ornamental mantels.

The object of the invention is to provide an ornamental mantel, which may be readily installed in old houses, where the foundation structure or building construction is insufficient to sustain heavy masonry, and in new houses at considerable less expense than the built-in constructions:

10 The invention further consists in the several features hereinafter set forth and more particularly defined by claims at the conclusion hereof.

In the drawings, Fig. 1 is a perspective view of a mantel embodying the invention;

15 Fig. 2 is a section taken on the line 2—2 of Fig. 1;

Fig. 3 is a section taken on the line 3—3 of Fig. 2;

20 Fig. 4 is a detailed sectional view taken on the line 4—4 of Fig. 2.

The ornamental mantel embodying the invention includes a layer 7 of lime mortar having particles partially embedded therein to form a facing representing jointed masonry. These particles may be stone or crushed glass placed in a suitable mold which in the case of stone has a mold face gouged out to represent a stone relief and in the case of brick has strips of steel along its sides to produce indentations resembling the mortar spaces between the bricks. The lime mortar is preferably colored and the layer 7 thus formed has some depth as, for instance, a thickness of three-quarters of an inch, and preferably consists of a suitable mixture of lime, sand, coloring material and water.

25 A foraminous metal reinforce 8, instanced here as consisting of one or more thin steel plates having openings punched therein, such as 9, is bent to shape and interposed between the layer 7 and a backing layer 10 of cinder concrete, it being understood that these openings permit passage of some of the material forming the layers through them to form a bond between the cinder concrete and the lime mortar.

30 In the case of mantels having stone facings the stones, such as 12 in Fig. 1, are put into suitable openings in the mold be-

fore the lime mortar is put into place. Fig. 1 shows a finished mantel structure having the imitation fire-place opening 5 formed therein.

35 By the term "imitation fire-place opening" I mean one in which no built-in flue structure is required, and of the type generally used in connection with gas or electrical heaters.

40 With the construction above described a light-weight structure of ornamental appearance is produced which may be readily kept in stock as a unit and can be readily installed in new or old buildings and be moved from one location to another in a manner similar to an article of furniture, such as a piano.

45 A hearthstone or slab 13 may also be associated with the wall structure, but is preferably separate therefrom.

50 What I claim as my invention is:

1. An ornamental mantel comprising a monolithic wall structure having an imitation fire-place opening and formed of a layer 55 of lime mortar having particles partially embedded therein to form a facing representing jointed masonry, a backing layer of cinder concrete, and a metal reinforce within the mantel.

60 2. An ornamental mantel comprising a monolithic wall structure having an imitation fire-place opening and formed of a layer of lime mortar having particles partially embedded therein to form a facing representing jointed masonry, a backing layer of cinder concrete, and a foraminous metal reinforce of substantially the same contour as the mantel interposed between the cinder concrete and the lime mortar, said layers of 65 lime mortar and cinder concrete being bonded together through the spaces in said reinforce.

65 3. An ornamental mantel comprising a monolithic wall structure having an imitation fire-place opening and formed of a layer of lime mortar having particles partially embedded therein to form a facing representing jointed masonry, a backing layer of concrete, and a foraminous metal reinforce interposed between the layers of 70 concrete and the lime mortar, said layers 75 of concrete and the lime mortar being bonded together through the spaces in said reinforce.

100

of concrete and lime mortar being bonded together through the spaces in said reinforcement.

4. An ornamental mantel comprising a monolithic wall structure having an ornamental facing including a layer of plastic material, a backing layer of a plastic material of different character than that of

the facing, and a foraminous metal reinforcement through the spaces of which said layers of plastic material are bonded, said reinforcement being of substantially the same contour as the walls forming the mantel.

In testimony whereof I affix my signature,
EMIL C. WEISSINGER.
